UNITED STATES PATENT OFFICE

ALFRED L. SCHULZE, OF HOUSTON, TEXAS

SADIRON HOLDER

Application filed October 4, 1929. Serial No. 397,207.

This invention relates to new and useful improvements in a sad-iron holder.

One object of the invention is to provide a holder or support, of the character described, specially designed for attachment to an ironing board to be used for supporting the iron when the same is not actually in use.

Another object of the invention is to provide a device of the character described which 10 may be easily attached to and detached from an ironing board and which will serve as a support for the sad-iron, when the same is not actually being used, to the end that the hot iron will not be liable to be left on the ironing board or the garment thereon to burn 15 the same.

With the above and other objects in view the invention has particular relation to certain novel features of construction, arrangement of parts and use, an example of which 20 is given in this specification and illustrated in the accompanying drawings wherein:—

Figure 1 shows a side view of the device as applied to an ironing board, and

Figure 2 shows a bottom plan view thereof.

Referring now more particularly to the drawings, wherein like numerals of reference designate similar parts in each of the 30 figures, the numerals 1, 1 designate the end bearings of a yoke member and the numerals 2, 2 designate diverging side arms of said yoke member whose outer ends 3, 3 are turned into substantial alignment with their free 35 ends 4, 4 turned outwardly into parallel relation. Between said parallel ends 4 there is a bar 5, whose outer end is upwardly curved and said bar is secured between said ends 4 by means of suitable bolts 6 which 40 also secure said ends together. Fastened to the respective portions 3, 3 are the angular upstanding clamps 7 adapted to engage over one edge of the ironing board 8. Slidably mounted in the bearings 1, 1 there is the shank 9 and a pull spring 10 connects the inner end of said shank to the inner end of the bar 5. The outer end of the shank 9 is formed into a hook like clamp 11 adapted to engage the other edge of the ironing board 8.

50 There are the supporting plates 12 whose

outer ends are downwardly turned and disposed in vertical relation, one on each side of the outer end of the bar 5 and these downwardly turned ends are clamped to said bar 5 by means of the clamp bolt 13. These plates are disposed in substantially horizontal position and their other ends 14, 14 are downwardly turned and bolted to the respective parts 3. Mounted on the plates 12 there is a platform 15, which is secured to said plates 12 and which preferably conforms to the shape of the sad-iron as shown. This platform has the upwardly extending, marginal, stops 16. While using a sad-iron it often becomes necessary to adjust the garment on the ironing board and usually there is no support for the said iron other than the ironing board itself, and when placed thereon, said iron is liable to burn the ironing board or the garment thereon. The attachment 70 herein described provides a convenient support on which the sad-iron may be located, when desired, so as to be at all times within convenient reach for use.

The spring 10 operates to hold the clamp 7, 11 in secure gripping relation with the margins of the ironing board; but, when it is desired to detach the holder, the clamp 11 may be pulled outwardly until it clears the corresponding edge of the board and then 80 swung downwardly to clear said bolt and the holder may then be removed from said board in an obvious manner.

The drawings and description disclose what is now considered to be a preferred form 85 of the invention by way of illustration only while the broad principle of the invention will be defined by the appended claims.

What I claim is:—

1. A sad-iron holder comprising a frame, spaced clamps thereon disposed to engage over opposite margins of an ironing board, yieldable means normally holding said clamps in such engaging relation one end of the frame being extended beyond the corresponding clamp and a supporting platform supported by said extended end.

2. A holder of the character described including a supporting frame having end clamps adapted to engage opposite edges of

an ironing board, said frame being extended at one end beyond the corresponding clamp and a supporting platform on said extended end.

3. An iron holder including a frame formed of two parts, a yieldable member connecting said parts, a clamp hook carried by each part, said hooks being engageable with opposite margins of a support, one end of the frame being extended beyond the corresponding clamp and a supporting platform on said extended end.

4. An iron holder including a frame, means thereon for engaging opposite margins of an ironing board, one end of the frame being extended beyond the corresponding engaging means and a supporting platform on said extended end of said frame.

5. An iron holder including a frame formed of sections, yieldable means connecting said sections, an engaging clamp on each section one end of the frame extending out beyond its corresponding clamp and an end supporting platform on said extended end of the frame.

In testimony whereof I have signed my name to this specification.

ALFRED L. SCHULZE.
